UNITED STATES PATENT OFFICE.

HUGH JAMES KINGSLEY, OF RUTLAND, VERMONT.

ICE-PICK.

SPECIFICATION forming part of Letters Patent No. 579,825, dated March 23, 1897.

Application filed April 24, 1896. Serial No. 588,928. (No model.)

To all whom it may concern:

Be it known that I, HUGH JAMES KINGSLEY, a citizen of the United States, and a resident of Rutland, in the county of Rutland and State 5 of Vermont, have invented certain new and useful Improvements in Ice-Picks, of which the following is a specification, reference being had to the accompanying drawings, forming a part thereof, in which similar letters of 10 reference indicate corresponding parts.

This invention relates to ice-picks; and the object thereof is to provide an improved device of this class which is adapted to be operated in the usual manner and which is also 15 provided with a sliding knocker or weight by which it may be driven into the ice and in connection with which I employ a spring-operated jaw or clamp by which pieces of ice may be picked up and carried.

20 The invention is fully disclosed in the following specification, of which the accompanying drawings form a part, in which—

Figure 1 is a side view of my improved ice-pick, and Fig. 2 a view at right angles thereto 25 with the spring-operated jaw or clamp removed.

In the practice of my invention I provide a knob or handle A, to which is secured a shaft a, the lower end of which is provided with a jaw 30 a², having teeth or projections a³. The shaft a is provided at a short distance above the jaw a² with a collar a⁴, and mounted on the shaft and adapted to slide thereon is a weight or knocker B, which is provided with a central longitudinal bore b, through which the 35 shaft passes, and said weight is also preferably provided in one side thereof with a longitudinal slot d².

The knob or handle A is preferably provided 40 with a neck a⁵, and mounted on the shaft a below said neck is a spiral spring C, and I also provide a rod D, the upper end of which is curved or bent at right angles and passed around the shaft a, so as to form an 45 arm d, on which the spring C rests, and the arm d is provided with an outwardly-directed hook or projection d².

The lower end of the rod D is curved outwardly, as shown at d³, and pivotally connected 50 with a lever G, which is pivotally connected with a shoulder or projection H, formed on the shaft a just above the jaw a², and the

lower side of the lever G is provided with a curved jaw or clamp g, which is adapted to operate in connection with the jaw a² for carrying pieces of ice. 55

The operation will be readily understood from the foregoing description when taken in connection with the accompanying drawings and the following statement thereof. 60

The rod D is provided near its lower end and on the inner side thereof with a spring K, which is provided with an inwardly-directed projection k, which is adapted to operate in connection with the collar a⁴ and serve 65 as a support for the jaw g and hold it out of contact with the jaw a², and said rod rests in the longitudinal slot b² of the weight or knocker B, and whenever it is desired to use the device as a pick it is held upright upon 70 the cake by the knob or handle A. The weight or knocker B is then raised, in which operation it strikes the arm d and raises the rod D until the projection k of the spring K rests upon the collar B, when the clamp or 75 jaw g will be about four inches away from the jaw a². The weight or knocker is then forced downwardly upon the collar a⁴, and thus will cut off a piece of ice and at the same time release the spring K, and the spring C will push 80 the clamp or jaw g downwardly firmly upon the piece of ice which has been cut off. The clamp or jaw g is also provided with teeth on its lower side which will operate in connection with the teeth on the jaw a², and said clamp 85 or jaw will hold the piece of ice as long as necessary.

In order to release the piece of ice, it is only necessary to pull upward on the projection or hook d². 90

This device is simple in construction and operation and is also comparatively inexpensive, and it is evident that changes in and modifications of the construction herein described may be made without departing from 95 the spirit of my invention or sacrificing its advantages.

Having fully described my invention, I claim as new and desire to secure by Letters Patent— 100

1. An ice-pick, comprising a knob or handle, a shaft connected therewith, which is provided at its lower end with a jaw having teeth formed thereon, and above said jaw with a

- collar, a knocker mounted on said shaft, and adapted to rest on said collar, a spring-operated rod, the upper end of which is connected with said shaft, and adapted to slide thereon, and the lower end of which is pivotally connected with a lever which is pivotally connected with said shaft, and which is also provided with a jaw or clamp, which is adapted to operate in connection with the jaw formed at the lower end of the shaft, and said rod being also provided with a spring which operates in connection with the collar formed on said shaft, substantially as shown and described.
- 15 2. An ice-pick, comprising a suitable knob or handle, a shaft connected therewith, and provided with a jaw, having teeth or projections at its lower end, a sliding weight or knocker mounted on said shaft and adapted to be supported by a collar formed thereon, and a rod, the upper end of which is connected with said

shaft by means of an arm which projects at right angles thereto, and on which rests a spiral spring which is mounted on said shaft, and the lower end of said rod being pivotally connected with a lever which is provided with a jaw which is adapted to operate in connection with the jaw formed on the shaft, and said rod being provided near its lower end with a spring which is secured to the inner side thereof, and provided with a projection which is adapted to operate in connection with said collar, substantially as shown and described.

In testimony that I claim the foregoing as my invention I have signed my name, in presence of the subscribing witnesses, this 13th day of April, 1896.

HUGH JAMES KINGSLEY.
